LOCK

John W. Fitz Gerald, Milwaukee, Wis., assignor
to Briggs & Stratton Corporation, Milwaukee,
Wis., a corporation of Delaware

Application November 5, 1934, Serial No. 751,573

8 Claims (Cl. 70—46)

This invention relates to improvements in locks and in its broader aspects is similar to that forming the subject matter of the copending application of John W. Fitz Gerald, Serial No. 751,572, filed November 5, 1934.

As in the invention of the aforesaid copending application, it is an object of the present invention to provide means operable upon breakage of a frangible part either as a result of percussive inward force or a strong outward pull applied to the cylinder during an attempt at unauthorized manipulation of the lock for positively rendering the cylinder ineffective to actuate the mechanism controlled.

More specifically it is an object of this invention to provide a cylinder lock wherein the cylinder is normally maintained against endwise movement by a frangible shear pin adapted to give way during an attempt at unauthorized manipulation, to permit the cylinder to move to a position at which other means secure the cylinder against further actuation.

Another object of this invention resides in the provision of spring pressed means normally maintained in a potentially operative condition to become operative and secure the lock cylinder against actuation upon movement of the cylinder to a predetermined position.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a longitudinal section view through a cylinder lock embodying this invention;

Figure 2 is a view similar to Figure 1, but showing the cylinder locked against subsequent actuation;

Figure 3 is a cross section view taken through Figure 2 on the plane of the line 3—3; and

Figure 4 is a top view of the assembled structure taken on a plane perpendicular to the plane on which Figures 1 and 2 are taken.

Referring now more particularly to the accompanying drawing, in which like numerals indicate like parts throughout the several views, the nu-

meral 5 designates the casing or shell of a cylinder lock having a bore 6 in which a lock cylinder 7 is mounted. The lock cylinder is inserted into the shell from the rear and has a reduced front end portion 8 preferably covered by a hardened metal cap 9 projecting through a correspondingly reduced bore 10 in the front end of the shell.

A frangible shear pin 11 fixed in the lock cylinder 7 with its outer end portion received in an arcuate slot 12 holds the cylinder against endwise movement and through engagement with the ends of the slot 12 defines its normal limits of rotation.

Any desired tumbler arrangement may be employed to lock the cylinder against rotation, and in the present instance the cylinder is provided with a locking bar 13 projectable from the side of the cylinder by key operable tumblers (not shown) for engagement in a longitudinal groove in the shell or casing 5. The tumblers, as is customary, are retractable by a proper key 14 inserted into the keyway 15 of the cylinder to free the cylinder for rotation.

Rotation of the cylinder may be imparted to mechanism to be controlled through the medium of a concentric cam 16 projecting from its rear end.

If an unauthorized attempt is made to manipulate the lock as by the insertion of an implement into the outer end of the keyway and the application of torsional force thereon, the connection between such implement and the keyway to be adequate to enable the transmission of the requisite turning force to the cylinder, generally requires that the implement be forcibly driven into the keyway a distance sufficient to afford a good grip.

During the application of the percussive force incidental to driving an implement into the keyway, the frangible shear pin 11 gives way and allows the cylinder to be driven inwardly endwise of the shell or casing 5. Upon such endwise shifting of the cylinder, two locking pins 17 snap into holes or recesses 18 in the shell or casing 5 to positively lock the cylinder against subsequent motion either rotational or longitudinal.

If the unauthorized manipulation of the lock is attempted through an outward pull on the cylinder and it is possible to apply a tool to the cylinder for the purpose without shearing the pin 11 and driving the cylinder inwardly, the outward endwise force on the cylinder will shear off the pin and allow outward endwise displacement of the cylinder. Upon such outward endwise movement of the cylinder, the locking pins 17 will again act

to lock the cylinder against subsequent motion, one of the pins 17 entering the arcuate slot 12 and the other snapping into a hole 18' diametrically opposite one end portion of the slot.

5 The locking pins 17 are housed within a hardened metal tubular sheath 19 disposed in a bore 20 extending transversely of the cylinder and are yieldably urged outwardly by an expansive spring 21 confined between the inner ends of 10 the pins. To limit the outward projection of the pins as they engage in their respective holes 18 and also add to the convenience in assembly, the outer ends of the pins are reduced in diameter to provide shoulders 22 which engage inturned flanges 23 on the outer ends of the tubular sheath 20.

When the locking pins 17 snap into their respective holes 18, the cylinder is firmly locked against actuation even though the proper key 20 be used, and by virtue of the fact that the tubular sheath 20 is formed of hardened metal, there is small likelihood of defeating the lock by drilling into the cylinder assuming that the hardened metal cap 8 could be chiseled off.

25 From the foregoing description taken in connection with the accompanying drawing, it will be readily apparent to those skilled in the art to which this invention appertains, that this invention affords simple, but highly effective means for 30 preventing unauthorized manipulation of a cylinder lock.

What I claim as my invention is:

1. In a lock, a bored mounting member, a lock 35 cylinder mounted therein, frangible means to hold the cylinder against endwise displacement in either direction, said means being adapted to give way under a percussive force applied to the cylinder to permit endwise displacement of the cylinder upon the application of percussive force on the cylinder, and means to positively lock the cylinder against rotation and endwise motion upon endwise displacement of the cylinder a predetermined distance.

2. In a lock, a bored casing, a lock cylinder rotatable therein in the performance of a normal locking and unlocking function, a locking pin adapted to interlock the cylinder and the casing upon endwise displacement of the cylinder with respect to the casing a predetermined distance, 45 a spring to automatically move the locking pin to its operative interlocking position, a hardened sheath enclosing the spring and the pin in a manner enabling projection of the pin therefrom, and frangible means engaging the cylinder and casing to normally hold the cylinder against endwise displacement, said frangible means giving way under an endwise force applied on the cylinder.

3. In a lock, a bored casing, a lock cylinder rotatable in the casing to effect a predetermined locking and unlocking function, means normally inactive but operable upon endwise displacement of the cylinder with respect to the casing to a predetermined position to interlock the cylinder 50 and casing and prevent the rotation of the cylinder necessary to effect its locking and unlocking function, and frangible means having engagement with the cylinder and casing to normally define the limits of said rotation of the cylinder

and hold the cylinder against endwise displacement, said means giving way under an endwise force applied to the cylinder to allow endwise displacement of the cylinder to the predetermined position at which the interlocking means secures the cylinder against further manipulation.

4. In a lock, a bored casing, a lock cylinder rotatable in the casing, means to define the normal limits of rotation of the cylinder and hold the cylinder against endwise displacement including a frangible part adapted to give way under an endwise force whereupon the cylinder is free to move out of its normal position with respect to the casing in the direction of the applied force.

5. In a lock, a bored casing, a lock cylinder mounted therein, a frangible shear pin carried by the cylinder and operating in an arcuate slot in the casing to define the normal limits of rotation of the cylinder and hold the cylinder in a 20 normal predetermined endwise position with respect to the casing, said frangible shear pin being adapted to give way under a percussive force applied on the cylinder to allow endwise displacement of the cylinder from its normal position.

25 6. In a lock, a bored casing, a lock cylinder mounted therein, a locking pin carried by the cylinder and yieldably urged to engage the wall of the casing bore and to snap into a hole in the casing communicating with its bore upon 30 endwise movement of the cylinder a predetermined distance, and frangible means to normally prevent endwise displacement of the cylinder to said predetermined position, said frangible means being adapted to give way under an endwise force applied on the cylinder.

7. In a lock, a bored casing having diametrically opposite holes communicating with its bore, a cylinder mounted in the casing, a locking unit having yieldably urged pins carried by the cylinder and normally engaging the wall of the casing bore so as not to interfere with rotation of the cylinder, said pins being adapted to snap into the holes in the casing upon endwise displacement of the cylinder to align the pins with 40 the holes, and frangible means to normally hold the cylinder against endwise displacement, said frangible means being adapted to give way under an endwise force applied on the cylinder.

45 8. In a lock, a bored casing having diametrically opposite holes communicating with its bore, a lock cylinder mounted in the casing and having a transverse bore adapted to align with the holes in the casing upon endwise displacement of the cylinder from its normal position, a locking unit 50 mounted in the transverse bore of the cylinder and comprising a pair of pins, a spring confined between the inner ends of the pins and tending at all times to push the pins outwardly of the periphery of the cylinder, a sheath enclosing the pins and the spring, said sheath being snugly received in the transverse bore in the cylinder, the outer ends of the pins being projectible from the sheath, means to limit outward projection of the pins with respect to the sheath, and frangible means to normally hold the cylinder against endwise displacement.

JOHN W. FITZ GERALD.
